Primary Examiner — Karen S Acker(74) *Attorney, Agent, or Firm* — Fross Zelnick Lehrman & Zissu, P.C.; Charles T. J. Weigell, Esq.(57) **CLAIM**

The ornamental design for a sheet material with surface pattern, as shown and described.

DESCRIPTION

The patent or application file contains at least one drawing/photograph executed in color. Copies of this patent with color drawing(s)/photograph(s) will be provided by the Office upon request and payment of the necessary fee.

The sole FIGURE is a plan view of a sheet material with surface pattern showing my new design.

The broken lines surrounding the figure depict the boundaries of the claim and form no part thereof.
